IRONING BOARD

Albert W. Behm, Milwaukee, Wis., assignor to
 Edward J. Frye, Gilbert L. Robbins, and
 Clarence H. Johnson, all of St. Paul, Minn.,
 copartners doing business as F. R. J. Sales
 Company, St. Paul, Minn.

Application October 31, 1934, Serial No. 750,753

3 Claims. (Cl. 68—10)

One of the objects of this invention is to provide an improved ironing board of the wall cabinet type which can be opened up and swung about into any one of a number of positions.

5 Another object is to provide an ironing board of the character described which is equipped with an auxiliary sleeve board.

Another object is to provide a self-contained ironing board unit in which the cabinet containing the board is a completely finished casing which can be applied easily to a wall without requiring any refinishing of the wall about the cabinet.

10 While the foregoing statements are indicative in a general way of the nature of the invention, other objects and advantages will be apparent to those skilled in the art upon a full understanding of the construction, arrangement and operation of the parts constituting this novel ironing board unit.

20 One embodiment of the invention is presented herein for the purpose of exemplification, but it will of course be appreciated that the invention is susceptible of embodiment in other structurally modified forms coming equally within the scope 25 of the appended claims.

In the accompanying drawing:

Fig. 1 is a horizontal section through the top of the ironing board cabinet, showing the door of the cabinet open and the ironing board swung 30 down and extended into one of its operative positions, and also showing the board in dotted lines in a different operative position;

Fig. 2 is a vertical section through the cabinet and board;

35 Fig. 3 is a front view of the cabinet, showing the door open and the board fully collapsed; and

Fig. 4 is a vertical transverse section through the board, taken on the line 4—4 of Fig. 2.

As will be observed in the drawing, the improved 40 unit includes an upright cabinet 10, a door 11 at the front of the cabinet, a two-part ironing board 12 which is normally housed in a collapsed condition within the cabinet, and a suitably insulated compartment 13 in the lower portion of the cabinet 45 inset below the board for the reception of an iron.

The cabinet 10, with the other parts just referred to, is a self-contained and fully finished unit, complete in itself, ready for application to a wall 14. The cabinet is provided about the 50 front thereof with a flange-like trimming frame 15, which frame may advantageously constitute the entire front of the cabinet. The frame 15 is formed as a permanent part of the cabinet and is adapted to flatly overlie and be fastened to the ordinarily rough edges of the hole which is cut in

the wall for the reception of the cabinet. The frame 15 not only gives a slight appearance to the installation by covering over the edge of the hole which otherwise would need to be refinished but it serves to position the cabinet properly with respect to the surface of the wall and provides an excellent lap structure for the reception of the screws or other securing means. The construction of the cabinet behind the front trimming frame 15 may in consequence be exceedingly simple—side, top, bottom and back walls 16 of thin 5 wood being sufficient to complete the cabinet.

The ironing board 12—which is composed of a short attaching section 17 and a relatively long utility section 18—is hinged at 19 to a cross member 20 in the lower part of the cabinet. The section 17, which is the part hinged to the member 20, is provided with a slot 21 which extends lengthwise of the section down the center of the same. The long remaining section 18 of the board 20 is lapped at its inner end over the outer end of the section 17 and carries a threaded bolt 22 which extends down through the slot 21 in the section 17 and is engaged by a clamping wing nut 23. By releasing the nut 23 the section 18 of the board 25 can be projected with respect to the section 17, from the collapsed position assumed by the parts when folded up in the cabinet, to the extended position shown in Figs. 1 and 2. The pivotal connection between the sections 17 and 18 provided 30 by the bolt 22 at the same time permits the main utility section 18 to be turned into any angular position which the user may desire, and by tightening up the nut 23 after the section 18 has been drawn out and turned, a rigid connection between 35 the sections will be established. The overlying section 18 is preferably spaced somewhat from the section 17 by cross ribs 24 and 25 on the overlapping ends of the sections. These ribs, in addition to maintaining the sections parallel to each 40 other, permit of an extremely rigid connection by allowing the clamping forces to be applied sharply along straight lines rather than contiguously over an area, and also allow for the application of the usual padding and cover (not shown) to the section 45 18 without interfering at all with either the sliding or the pivoting of the section 18 relative to the section 17.

The section 18 of the ironing board is provided intermediate its ends with a pair of interconnected supporting legs 26 which are hinged at 27 to a cross member 28 on the bottom of the section. After the cabinet door 11 has been opened, and the board 12 swung down into a horizontal position and then extended, the legs 55

26 may be swung down from underneath the board into the slightly inclined position shown in Fig. 2, in which position the legs will hold the board quite solidly regardless of the angle 5 to which the long upper section 18 of the board may have been turned about the pivot bolt 22. Rubber pads 29 are preferably attached to the lower end of the legs for cushioning the board, compensating for irregularities in the floor, and 10 offering friction to sidewise movement.

The long upper section 18 of the board is provided on its under side with a small sleeve board 38 which is pivoted on a bolt 31 and can be swung from a position beneath the section 18 into the 15 laterally projecting position shown in Fig. 1. The bolt 31 on which the board 30 is mounted is provided with a wing nut 32 for clamping the board against movement in any desired position. When in its projected position the board 30 20 closely overlies a small metal bracket 33 which is attached to the cross member 28 beneath one of the edges of the section 18. The bracket 33 will absorb practically all pressure which is applied to the board 30 when the latter is being 25 used.

When the ironing board is ready to be closed up in the cabinet, the sleeve board 30 is swung back under the section 18, the two sections 17 30 and 18 are slid together, and all of the parts are then swung upwardly into the cabinet, the lugs 26 being folded back against the under side 35 of the board at the same time. After all of the parts are inside the cabinet the upper free end of the sleeve board 30 can be swung laterally a little into the position shown in Fig. 3, behind a corner piece 34, which corner piece will lock the ironing board and its associated parts against outward movement while the door 11 is being closed.

If, for any reason, it is impractical to cut a 40 hole in the wall for the reception of the cabinet, a slightly modified form of cabinet may be employed in which the trimming frame 15 which is used in fastening the cabinet to the wall is located about the back edge of the cabinet instead 45 of the front edge. This change in the location of the trimming frame will permit the cabinet to be secured in a projecting position with its back against the wall.

I claim:

1. An ironing board unit comprising a cabinet, an ironing board which is mounted in the cabinet in a collapsed but readily extendable condition, said board including an attaching section which is hinged to the cabinet for swinging movement about a horizontal axis, and a utility section which is arranged with its inner end in overlapped relation to the outer end of the attaching section, ribs on the overlapping ends of the sections for 10 maintaining the same in spaced parallel relation, and a clamping bolt on the under side of the lapping portion of the utility section extending downwardly into a longitudinal slot in the underlying portion of the attaching section for permitting the utility section to be slid longitudinally of and pivoted relative to the attaching section. 15

2. An ironing board unit comprising a cabinet, an ironing board which is mounted in the cabinet, and a sleeve board which is pivoted to the under 20 side of the ironing board for movement from an inoperative position beneath the ironing board to an operative position at one side of the latter, means for clamping the sleeve board in its operative position, and a corner piece in one of the 25 front upper corners of the cabinet behind which the free end of the sleeve board is adapted to be swung when the unit is in its collapsed condition, whereby to lock the ironing board and associated parts within the cabinet. 30

3. An ironing board unit comprising a cabinet, an ironing board which is mounted in the cabinet in a collapsed but readily extendable condition, said board including an attaching section which is hinged to the cabinet for swinging movement about a horizontal axis, and a utility section which is arranged with its inner end in overlapped relation to the outer end of the attaching section, projections on the overlapping ends of the sections for maintaining the same in spaced 35 parallel relation, and a clamping bolt on the under side of the lapping portion of the utility section extending downwardly into a longitudinal slot in the underlying portion of the attaching section for permitting the utility section to 40 be slid longitudinally of and pivoted relative to the attaching section. 45

ALBERT W. BEHM.
